CLAIM

The ornamental design of a package with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top planar view of a package with surface ornamentation illustrating our new design, wherein the package is in an unfolded orientation;

FIG. 2 is a perspective view of a package with surface ornamentation illustrating our new design, wherein the package is in a folded orientation;

FIG. 3 is a front side elevational view thereof;

FIG. 4 is a back side elevational view thereof;

FIG. 5 is a left side elevational view thereof;

FIG. 6 is a right side elevational view thereof; and,

FIG. 7 is a top planar view thereof.

The broken lines form no part of the claimed design.
